US00D879077S

(12) **United States Design Patent** (10) Patent No.: **US D879,077 S**
(45) Date of Patent: ** *Mar. 24, 2020

(54) **CROSSOVER FOR RFID IC TERMINALS**

(71) Applicant: **Impinj, Inc.**, Seattle, WA (US)

(72) Inventor: **Ronald A. Oliver**, Seattle, WA (US)

(73) Assignee: **Impinj, Inc.**, Seattle, WA (US)

(*) Notice: This patent is subject to a terminal disclaimer.

(**) Term: **15 Years**

(21) Appl. No.: **29/590,787**

(22) Filed: **Jan. 13, 2017**

(51) LOC (12) Cl. **14-03**

(52) U.S. Cl.

USPC **D14/230**

(58) **Field of Classification Search**
